UNITED STATES PATENT OFFICE.

BENJAMIN W. TUCKER, OF NEWARK, NEW JERSEY.

CAR-TRUCK.

SPECIFICATION forming part of Letters Patent No. 592,843, dated November 2, 1897.

Application filed July 19, 1897. Serial No. 645,125. (No model.)

To all whom it may concern:

Be it known that I, BENJAMIN W. TUCKER, a citizen of the United States, and a resident of Newark, in the county of Essex and State 5 of New Jersey, have invented certain new and useful Improvements in Car-Trucks, of which the following is a specification.

The invention relates to improvements in car-trucks, and pertains particularly to the 10 side frames or beams and the pedestals formed at the ends of the side frames to receive the axle-boxes and admit of the latter having a vertical reciprocating movement, as herein-after described and claimed.

15 In accordance with this invention the side frames of the truck are duplicates of one another, and each is preferably formed of a continuous rolled beam having upper and lower inwardly-turned edge flanges and an inner 20 flanged section applied to each end of said rolled beam and having its outwardly-turned flanges secured to the inwardly-turned flanges of said beam, whereby a box-like structure is formed at each end of each side frame to 25 receive the car-springs. The pedestal-space is formed at each end of each side frame in said box-like structure and completed by a 30 wrought-metal strap secured to the lower flanges of said beam and inner flanged section.

The object of my invention is to produce a car-truck frame of great efficiency and durability and capable of withstanding the severe usage to which car-truck frames are subjected.

35 The invention will be fully understood from the detailed description hereinafter presented, reference being had to the accompanying drawings, in which—

40 Figure 1 is a side elevation, partly broken away and partly in section, of a car-truck frame constructed in accordance with and embodying my invention. Fig. 2 is a like view of one end of the side frame, the spring over 45 the axle-box being omitted. Fig. 3 is an end view of a portion of said truck-frame; and Fig. 4 is a top view, partly broken away and partly in section, of same.

In the drawings, A designates the main side 50 frame or beam, having the upper and lower inwardly-turned flanges, (lettered B C, respectively,) and D the inner end sections, prefer-

ably of cast metal, having the outwardly-turned upper and lower flanges E F, which, as shown, are secured to the aforesaid flanges B 55 C of the main side beam. The main side beam A has formed in it adjacent to its ends the recesses G of rectangular outline and forming a part of the pedestal-spaces for the axle-boxes H. The recesses G are cut upward into the 60 beam A from the lower edge thereof. The upper and lower flanges B C of the side beam A are preferably thicker than the web portion of said side beam.

The inner end sections D, applied to the 65 inner sides of the ends of the side beams A, correspond with one another, and the upper flange E of each of said inner sections preferably passes over the upper flange B of the side beam A, while the lower flanges F of said 70 inner sections pass outward over the lower flange C of the said side beam A. The inner end sections D are each formed with the recess I, corresponding with the recess G, formed in the side beam A, but preferably at the upper portion greater in width than said recess G, as indicated by dotted lines in Fig. 1 and full lines in Fig. 2. The inner end sections D are each formed with the vertical flanges J and horizontal flanges K, the former of 75 80 which are at opposite sides of the lower portion of the said recess I and constitute rubbing-surfaces for the axle-boxes H. The rubbing-flanges J extend between the lower horizontal flanges F of said end sections D and 85 the upper flanges K, the latter affording increased strength to the rubbing-flanges J, as well as to the inner end sections D. The inner end sections D are preferably each cast in one integral piece, and each comprises the 90 vertical web portion L, the upper outwardly-extending flange E, the lower outwardly-extending flanges F, the rubbing-flanges J, and the horizontal flanges K, the latter being at the upper ends of the rubbing-flanges J and 95 coextensive in width with the lower flanges F. When the inner cast sections D are in position, the upper flange E thereon will extend outward to the outer vertical face of the side beam A, and the flanges F J K of the 100 said end sections D will extend outward to contact with the inner vertical face of the web of the side beam A.

As indicated in Fig. 2, the rubbing-flanges

J extend inward toward one another beyond the vertical sides of the space I, formed in the inner flanged section D, and the inner facing sides of the flanges J are on a vertical plane with the sides of the recess G, formed in the side beam A, as indicated in Fig. 1, and also on a vertical plane with the opposite facing sides of the strap M, as shown in Fig. 2. The strap M will preferably be formed 10 of wrought metal and have its ends bent outward from one another to contact with the lower surface of the flange C of the side beam A. The strap M receives the lower portion of the axle-box II and is secured in position 15 by the bolts N, which, as more clearly illustrated in Fig. 2, extend through the lower flanges F of the inner section D, the lower flange C of the side beam A, and the ends of the strap M. At the outer ends of the flange 20 or flanges F at the lower edge of the inner section D are formed the small flanges O, contacting with the heads of the bolts N to prevent said bolts from turning axially under the jarring action of the truck. 25 The inner end sections D at their lower portions correspond in width with the width of the flanges of the side beam A, but at their upper portions, as indicated in Fig. 3, extend inward, so as to form abundant space 30 between their web L and the web of the side beam A to receive the elliptic spring P, which, as illustrated in Fig. 1, is held between the upper surface of the axle-box II and the lower surface of the upper flange B of the 35 side frame A. The lower surface of the upper flange B of the side beam A contains the recess Q to receive the small projection R, carried by the upper band of the spring P, and the upper surface of the axle-box II is 40 formed with the gibs S to receive the lower edges of the lower band of said spring P, and thus the spring P both at its lower band and upper band is securely held against displacement and directly over the axle-box II. The 45 inward projection of the upper portion of the web L of the inner section D to receive the spring P necessitates a greater width in the recess I than the recess G of said beam A, in order that the flanges on the axle-box 50 II during their upward movement will above the flanges J have free play, as illustrated in Fig. 2. If the spring P were narrower, the web of the inner section D would not require to be projected along its upper portion, and 55 under such condition the recess I would correspond in width with the recess G. It is desirable, however, to employ a spring P of requisite dimensions, and hence the upper portion of the inner section D should ordinarily be projected inward, as indicated in Fig. 3, so as to form abundant space for said spring. The upper flange E of the inner section D is secured to the upper flange B of the side beam or frame A by means of the rivets 60 T, and the lower flanges F of said inner section are secured to the lower flange C of the side beam or frame A by means of the bolts 65

N, which, in addition to connecting the inner section D and the side beam or frame A, also secure the pedestal-strap M in place. 70

The axle-box II is held within the pedestal-space formed by the beam A, inner section D, and strap M, and is adapted to have a vertical reciprocation within said space. 75

By means of the present invention I am enabled to produce a very strong truck at comparatively small expense and with the minimum amount of hand labor. The side beam A is in a continuous piece of rolled beam cut off square at its ends and having the recesses 80 G formed therein adjacent to said ends. The inner end sections D are, as above indicated, preferably cast in one integral piece to fit the inner sides of the ends of the side beam A, and said inner sections D, while furnishing the rubbing-surfaces for the axle-boxes, form box-like structures at the ends of each side frame to receive and protect the springs P and serve to connect the upper and lower flanges B C of the side frame A, thereby strengthening the truck-frame and completing a structure capable of withstanding the severe usage to which car-truck frames are ordinarily subjected. 85 90 95

The strap M is shown in its best form and as an integral piece of wrought metal bent to the required shape to inclose the opposite sides and lower end of the axle-box, said strap thus constituting the lower portion of the pedestal-frame. The invention is not limited, 100 however, to the special strap M shown, since said strap may be made in several connected pieces, if preferred, instead of one piece, in a manner well known in this art. The term "strap," therefore, is not to be taken as a word 105 of special limitation.

What I claim as my invention, and desire to secure by Letters Patent, is—

1. In a car-truck, the side frames having upper and lower flanges and provided with the pedestal-recesses at their ends, and the flanged end sections applied to the ends of said side frames and having recesses in line with the aforesaid recesses, said end sections being projected at their upper vertical longitudinal portions in a direction from said side frames to form, with said side frames, receiving-spaces for springs, combined with the pedestal-straps below said recesses, the axle-boxes held in said recesses and strap, and springs above said boxes and housed within said spaces; substantially as set forth. 110 115 120

2. In a car-truck, the side frames having upper and lower flanges and provided with the pedestal-recesses at their ends, and the flanged end sections applied to the ends of said side frames and having recesses in line with the aforesaid recesses, said end sections being projected at their upper vertical longitudinal portions in a direction from said side frames to form, with said side frames, receiving-spaces for springs, and formed integral with vertical rubbing-flanges for the axle-boxes, combined with the pedestal-straps be- 125 130 135

low said recesses, the axle-boxes held in said recesses and strap, and springs above said boxes and housed within said spaces; substantially as set forth.

5 3. In a car-truck, the side frames having the upper and lower flanges and provided with the pedestal-recesses at their ends, and the flanged end sections connecting the flanges of said side frames and having recesses in line 10 with the said recesses in said side frames, said end sections being projected at their upper vertical longitudinal portions in a direction from said side frames to form, with said side frames receiving-spaces for springs, combined 15 with the pedestal-straps below said recesses, the axle-boxes held in said recesses and strap, and springs above said boxes and housed within said spaces; substantially as set forth.

4. In a car-truck, the side frames provided 20 with the pedestal-recesses and having the upper and lower edge flanges projecting from one side thereof a distance substantially corresponding with the width required for the rubbing-surfaces of the axle-boxes, and the 25 end sections having the edge flanges to engage the flanges of said side frames and having also the pedestal-recesses in line with the pedestal-recesses in said side frames, combined with the pedestal-straps below said recesses and completing the pedestal-spaces, the axle-boxes in said spaces, the rubbing-surfaces for the axle-boxes at one side of said side frames and above the lower flanges of the latter, and the springs substantially centrally 30 over the axle-boxes and their rubbing-surfaces and housed at one side of the side frame between the latter and the vertical longitudinal portions of said end sections; substantially as set forth.

40 5. A car-truck frame comprising the side frames having the upper and lower edge flanges and provided at each end with the recess G, and the end sections D having the edge flanges engaging the upper and lower flanges of the side frame, said sections D being formed with the recess I and rubbing-flanges J, combined with the straps M forming the lower part of the pedestals, the axle-boxes, and the spring for said boxes and between the side frame A and the said sections D; substantially as set forth.

6. In a car-truck, the side frame A having the flanges at its upper and lower edges and formed at its ends with the recesses G, and the end sections D having the flanges E, F, vertical rubbing-flanges J, horizontal flanges K and recesses I, the latter being in alignment with the said recesses G; combined with the pedestal-straps M secured to the side frame and completing the pedestals for the axle-boxes, and a spring over each axle-box; substantially as set forth.

7. In a car-truck, the side frames having the upper and lower edge flanges and formed 65 at their ends with the recesses G, and the end

sections D having the edge flanges and recesses in line with the said recesses G, said sections D being formed integral with the rubbing-flanges J and horizontal flanges K, combined with the pedestal-straps M below 70 said recesses and having their ends bent outward from one another, the bolts passing through the lower flanges of said inner section D, the flanges C of the said frames A, and said ends of said straps, and the springs 75 above the axle-boxes; substantially as set forth.

8. In a car-truck, the side beams or frames A having the upper and lower flanges, and the sections D having the upper and lower 80 flanges and provided with recesses I, the upper portion of said sections D being projected from the side frames, combined with the rubbing-flanges for the axle-boxes, the springs over said boxes and housed between said side 85 beams A and said sections D, and the pedestal-straps M receiving the lower portion of the axle-boxes, the ends of said side beams A having the recesses G in line with said rubbing-flanges J and pedestal-straps M; sub- 90 substantially as set forth.

9. In a car-truck, the side beams A having the upper and lower flanges and provided with the end recesses G, combined with the end sections D having the upper and lower 95 flanges and recesses I greater in width at their upper portion than said recesses G, the rubbing-flanges for the axle-boxes between said side beams A and end sections D and in line with the edges of said recesses G, the straps 100 M receiving the lower portion of the axle-boxes and having their inner vertical sides in line with said rubbing-flanges, and the springs above said axle-boxes; substantially as set forth.

10. In a car-truck, the side frames A having the upper and lower flanges and provided with the recesses Q and end recesses G, and the end sections D having the upper and lower flanges and provided with the recesses in line 110 with said recesses G, combined with the pedestal-straps below said recesses and completing the pedestal-spaces, the rubbing-flanges in line with the inner vertical sides of said straps, the axle-boxes within said spaces and 115 having the flanges S upon their upper ends, and the spring P interposed between the said beam A and inner end section D and having the projection R to enter said recess Q and having its lower band adapted to enter the 120 space outlined by said flanges S; substantially as set forth.

Signed at Newark, in the county of Essex and State of New Jersey, this 16th day of July, A. D. 1897.

BENJAMIN W. TUCKER.
